CLAIM

The ornamental design for a display screen with a graphical user interface for a messaging application, as shown and described.

DESCRIPTION

FIG. 1 is a front view of a first image of a first embodiment of a display screen with a graphical user interface for a messaging application; and,

FIG. 2 is a front view of a second image of a second embodiment of a display screen with a graphical user interface for a messaging application.

The broken lines are environmental only and form no part of the claimed design. The outer rectangle in broken lines is included to show a portion of an example display screen and forms no part of the claimed design.

1 Claim, 2 Drawing Sheets
